(57) **CLAIM**

The ornamental design for a bottle, as shown and described.

DESCRIPTION

FIG. 1 is a perspective view of a bottle showing our new design;

FIG. 2 is a side elevational view thereof; and,

FIG. 3 is a top plan view thereof.

The dot-dot-dot broken lines shown in the drawings are for illustrative purposes only and form no part of the claimed design.

The dot-dash-dot broken lines shown in the drawings define the boundaries of the claim.
